UNITED STATES PATENT OFFICE

133,124

DESIGN FOR A BADGE OR THE LIKE

William E. Hoffmann, University City, Mo.

Application January 19, 1942, Serial No. 105,314

Term of patent 3½ years

To all whom it may concern:

Be it known that I, William E. Hoffmann, a citizen of the United States, residing in University City, St. Louis county, State of Missouri, have invented a new, original, and ornamental Design for a Badge or the like, of which the following is a specification, reference being had to the accompanying drawing, forming part thereof.

Fig. 1 is a front elevational view of a badge showing my new design; and

Fig. 2 is an edge view thereof.

The drawing is lined for color.

The characteristic feature of my ornamental design for a badge or the like resides in disposition of the A and V in respect to the background effecting a star.

I claim:

The ornamental design for a badge or the like, substantially as shown and described.

WILLIAM E. HOFFMANN.
